UNITED STATES PATENT OFFICE.

WILLIS LUTHER MOORE, OF PASADENA, CALIFORNIA.

HUMIDIFYING RADIATOR.

Application filed May 21, 1924. Serial No. 714,829.

To all whom it may concern:

Be it known that I, WILLIS LUTHER MOORE, a citizen of the United States, residing at Pasadena, in the county of Los Angeles and State of California, have invented new and useful Improvements in Humidifying Radiators, of which the following is a specification.

My invention relates to a humidifying radiator for heating rooms of a dwelling, and it is a special object of this invention to provide a simple, inexpensive, and easily regulated apparatus, whereby heat is homogeneously distributed by means of aqueous vapors which will quickly diffuse itself throughout the room giving and maintaining heat at substantially the same temperature at every point of the room, near the floor as well as near the ceiling.

It is another object of this invention to provide a radiator composed of a series of horizontally disposed radiator units, each consisting of a water receptacle open at the top, with a heating pipe passing successively through the radiator units. In each unit the heating pipe is bent upon itself to form two horizontal sections, one immersed in water, the other exposed to the atmosphere at least in part. Means may also be provided for supplying water from the heating pipe, if the latter is a hot water pipe, to the radiator units with automatic means for maintaining the water in each unit at a substantially constant level.

Other objects will be apparent from the subsequent description.

In the accompanying drawings, which form a part of the specification:

Figure 1 shows a sectional view of a part of a dwelling showing a room equipped with a humidifying radiator and a source of heat therefor.

Fig. 2 is a vertical longitudinal section of the humidifying radiator, and

Fig. 3 is a perspective view of a section of the radiator.

Referring to the drawings, 1 indicates the interior of a room of a dwelling, on the roof of which there is a solar heater consisting of a plurality of solar reflectors 2 heating the water in a coil 3 for a hot water tank 4 which is connected by means of a pipe 5 controlled by a valve 6 to a radiator 7. 8 designates a pipe supplying water under pressure to the hot water reservoir 4.

The humidifying radiator consists of end

walls 9, 9, between which a series of horizontally disposed humidifying radiator units 10 are disposed, spaced from each other and in vertical alinement. Five of such units are shown in Fig. 2. Each radiator unit consists of a box-like receptacle, open at the top, the end walls of the radiator units 10 being formed by the vertical walls 11, 11, which are spaced from the end walls of the radiator. Front and rear walls 12, 12', connecting end walls 9, 9, form vertical chambers 16, 16' respectively. The top of each radiator unit is covered by a screen 13.

The hot water from the solar heater enters the lowermost radiator unit 10 by means of a pipe 14 connected to the pipe 5. Said pipe 14 passes successively through each of the radiator units 10, and is bent upon itself in each radiator unit 10 to form a lower horizontal pipe section 14¹ permanently immersed in water and an upper horizontal pipe section 14², which in the lowermost radiator unit 10, is entirely exposed to the atmosphere, while in the other radiator units it is partly exposed to the atmosphere. In the uppermost radiator unit 10 the hot water pipe 14 forms a return bend 14³ above section 14², leaving the radiator unit at 15, passing downwardly in the chamber 16, and through the end wall 9 at 17, to return to the system and ultimately to the reservoir 4. A water pipe 18 controlled by a valve 19 supplies water to the topmost radiator unit 10. A series of overflow pipes 20 conducts the water from each radiator unit to the one immediately below. The lowermost radiator unit is provided with an overflow pipe 21, leading to a waste pipe, (not shown).

In place of having a separate water pipe 18, as shown in Fig. 2, the hot water pipe 14 may supply the water for the topmost radiator unit 10 by means of a pipe 18' connected to the hot water pipe 14. A float operated valve 22 controls the flow of water from pipe 14 through pipe 18'.

In the operation of the radiator, the units 10 are filled with water and are maintained to a predetermined level by means of the overflow pipes 20, as will be understood. The heat is supplied to the radiator units by means of the hot water pipe 14, and the room is heated not only by convection and radiation, but principally by the aqueous vapor given off from each radiator unit 10, which passes from the open top of each unit 10 into the room where the vapor will, be-

cause of its diffusion, uniformly and quickly distribute the heat throughout the room and maintain the same at substantially the same temperature at all points of the room.

8 While I have shown the hot water supplied by a solar, it will be understood that the hot water may be supplied by any other suitable or preferred means, nor do I limit my invention to hot water as a heat supplying means, but may use steam in place thereof, or even hot air. Where steam or hot air is used, it will be necessary, however, to use a separate water pipe 18 for supplying water to the radiator units 10.

15 Various changes may be made in the arrangement and construction of parts by those skilled in the art without departing from the spirit of my invention as claimed.

I claim:

20 1. In a humidifying radiator, the combination of a series of horizontally disposed radiator units, each consisting of a water receptacle exposed at the top to the atmosphere, a hot water conduit passing horizon-

tally through each unit, the hot water conduit in each unit consisting of two horizontal sections, one immersed in the water and the other exposed to the atmosphere, at least in part, and automatic means for supplying water from the hot water conduit to each unit and maintaining the same at a substantially constant level.

2. In a humidifying radiator, the combination of a series of horizontally disposed radiator units, each consisting of a water receptacle exposed at the top to the atmosphere, a hot fluid conduit passing horizontally through each unit, the hot fluid conduit in each unit consisting of two horizontal sections, one immersed in the water and the other exposed to the atmosphere at least in part, means for supplying water to each unit and means for maintaining the water in each unit at a substantially constant level.

In testimony whereof I have signed my name to this specification.

WILLIS L. MOORE.
